ATTORNEY.

UNITED STATES PATENT OFFICE.

HERMAN A. WILHELM, OF LA PORTE, INDIANA.

DESIGN FOR A MILK-SEPARATOR.

SPECIFICATION forming part of Design No. 31,590, dated October 3, 1899.

Application filed September 11, 1899. Serial No. 730,180. Term of patent 14 years.

To all whom it may concern:

Be it known that I, HERMAN A. WILHELM, a citizen of the United States, residing at La Porte, in the county of La Porte and State of Indiana, have invented and produced a new and original Design for Milk-Separators, of which the following is a specification, reference being had to the accompanying drawings, forming a part thereof, in which—

Figure 1 is a side elevation of a separator made after my new design, and Fig. 2 is a bottom plan view of the same.

Referring to the drawings, the essential and material features of my design are the tube *a* and the convex disk *b*. The said tube is open at both ends, the top is of larger diameter than the bottom or lower end, and the

sides taper between said top and bottom. The disk *b* is convex or curved upwardly, is formed with a central opening *c*, which registers with the lower end of the tube to which it is secured, and has formed therein a plurality of small openings *b'*.

Having thus described my invention, what I claim as new, and desire to secure by Letters Patent, is—

The design for a milk-separator substantially as herein shown and described.

In testimony whereof I affix my signature in presence of two witnesses.

HERMAN A. WILHELM.

Witnesses:

GEORGE OLTSCHE,
HUGO OLTSCHE.
